UNITED STATES PATENT OFFICE.

LOCKSLEY W. ABBOTT, OF DELAWARE, OHIO.

METALLIC RAILWAY-TIE.

1,054,660.

Specification of Letters Patent. Patented Mar. 4, 1913.

Application filed December 18, 1912. Serial No. 737,041.

To all whom it may concern:

Be it known that I, LOCKSLEY W. ABBOTT, a citizen of the United States of America, residing at Delaware, in the county of Delaware and State of Ohio, have invented certain new and useful Improvements in Metallic Railway-Ties, of which the following is a specification.

This invention relates to metallic railway ties, and its object is to provide an improved device of this character constructed in such manner that while it may be formed entirely of metal, it will not be open to the objection that it is unduly rigid and unyielding.

One of the principal objections to some of the metallic and concrete ties heretofore devised is that they have presented too unyielding a road bed and their use has caused serious wrecks.

It is a further object of the invention to provide a tie of the character above set forth constructed in such manner that it may be very economically manufactured.

A still further object is the provision of improved means for securing the rails upon the ties.

Further objects and advantages of the invention will be set forth in the detailed description which now follows.

In the accompanying drawing, Figure 1 is a perspective view of a metallic tie constructed in accordance with the invention. Fig. 2 is a transverse sectional view therethrough, and Fig. 3 is a partial longitudinal sectional view therethrough.

Like numerals designate corresponding parts in all of the figures of the drawing.

This improved metallic tie comprises a substantially U-shaped base consisting of a bottom 5 and upturned side wall 6. The rails are supported upon yielding, metallic chairs consisting of a base plate 7 riveted or otherwise secured at 8 to the bottom 5 and being bent therefrom to form an upstanding side wall 9 which lies inside of one of the side walls 6, then bent into bow formation at 10, then bent into substantial parallelism with base plate 7 at 11 and lying thereabove, then bent into bow formation at 12, then bent to form a vertical side wall 13 and then joining the base plate 7, the overhanging bow portions 10 and 11 resting upon the upper edges of the side walls 6. The rails of course extend transversely of

the tie, as indicated in dotted lines at the right hand side of Fig. 1 and rest upon the comparatively wide and plane surfaces 11. Slits 15 are formed through these plane surfaces for the reception of the legs 17 of U-shaped clips. The body portion 18 of these clips lies beneath the tops of the chairs and the legs 17 extend through slots 15. After the rails have been placed in position, these legs are bent at 17 to engage the base flange 65 of the rail in a manner that will be readily understood.

The structure herein shown and described may be very economically manufactured and by the employment thereof, tracks may be laid with great rapidity. This structure renders the ties comparatively light and easily handled and the clips comprising the parts 17 and 18 provide means for rapidly securing the rails in position. The bow formation of the portions 10 and 12 causes the chairs to absorb much of the vibration induced by the passage of trains at high speed, and this not only reduces noise and wear and tear upon the rolling stock, but it prevents loosening up of the nuts and bolts that hold the fish plates and the rails together.

While the elements shown and described are well adapted to serve the purposes for which they are intended, it is to be understood that the invention is not limited to the precise construction set forth, but includes within its purview such changes as may be made within the scope of the appended claim.

Having described my invention, what I claim is:

A metallic railway tie comprising a bottom and vertical side walls in combination with yielding metallic chairs, comprising a top spaced from and lying above said bottom, base portions lying between said vertical side walls and bowed portions connecting said base portions and said top, said bowed portions overhanging and resting upon the upper edges of said vertical side walls.

In testimony whereof I affix my signature in presence of two witnesses.

LOCKSLEY W. ABBOTT.
